UNITED STATES PATENT OFFICE.

WILLIAM J. BOEMPER, OF RUTHERFORD, NEW JERSEY, ASSIGNOR OF ONE-HALF TO HIMSELF,
AND ONE-HALF TO HARRY A. MUECKE, OF NEW YORK, N. Y.

ATTACHMENT FOR SAFETY-FUSES.

No. 904,928.

Specification of Letters Patent.

Patented Nov. 24, 1908.

Application filed October 4, 1907. Serial No. 395,840.

To all whom it may concern:

Be it known that I, WILLIAM J. BOEMPER, a citizen of the United States, residing at Rutherford, in the county of Bergen and State of New Jersey, have invented an Improvement in Attachments for Safety-Fuses, of which the following is a specification.

Heretofore so far as I am aware, considerable difficulty has been experienced in separating safety fuses from the clip terminals in which the same are connected in a fuse box and other electrical fittings, and this because of the nicety of the fit between the terminals of the safety fuse devices and the clip terminals in which the same are inserted and also because of the strength of the spring in clip terminals which has to be overcome in removing the fuse terminals therefrom.

The object of my present invention is to overcome the hereinabove mentioned difficulties by the provision of a device adapted to be attached to a spring clip terminal, a knife-blade terminal or other form of safety fuse terminal clip and by the use of which the safety fuse can be readily removed from its operative position in the clip terminal.

In carrying out my invention, I employ two members pivotally secured together and each adapted to be connected to an opposing part of the safety fuse terminal clip, and means by which pressure may be employed and transmitted through said members to the said opposing parts of the terminal clip to spread the same in order that the fuse with its terminals may be readily withdrawn.

In the drawing, Figure 1 is a perspective view illustrating a spring clip terminal with a safety fuse connected therewith and my improved attachment in position thereon. Fig. 2 is a perspective view of a knife-blade terminal showing the fuse terminal inserted therein and Fig. 3 is a perspective view of a modified form of the attachment adapted for use upon the terminal shown in Fig. 2.

Referring to the drawing and particularly to Fig. 1, *a* designates a base of any suitable insulating material upon which a spring clip safety fuse terminal *b* is to be secured by means of a screw or bolt *c* or otherwise. As is customary, the spring clip terminal comprises oppositely disposed members *d e* adapted to receive and to make electrical

connection with the end cap or terminal *f* of the safety fuse device *g*, and the opposing members *d e* of the fuse clip are commonly provided with in-turned lugs or ears indicated at *h h'*.

Now my improved attachment comprises two suitably curved arms *i* and *l* pivotally connected together by a screw or pivot *m* and in its outer edge adjacent to the free end the arm *i* is provided with an undercut recess indicated at *i'* adapted to receive that portion of the in-turned lug *h* adjacent to the member *d* of the fuse clip, and similarly the arm *l* is provided with an undercut recess adapted to receive the corresponding portion of the lug *h'* by means of which the arms in their pivotally connected relation are both supported upon and secured to these lugs *h h'* and are readily removable therefrom. I also employ a thumb-piece *n* which as shown in Fig. 1, is made integral with the arm *l* and turned over at right angles thereto adjacent to the point in which the arm *l* is pivotally connected to the arm *i*. It will be apparent however, that this thumb-piece *n* may without departing from the nature and spirit of my invention, turn outwardly instead of inwardly, or may if desired be mounted upon the same pivot by which the arms are connected instead of being made integral with one of the arms. It will also be apparent that by applying pressure to the thumb-piece *n* the same will be transmitted through the arms *i* and *l* and cause the opposing parts *d e* of the spring clip to spread in order that the safety fuse may be readily removed therefrom.

I have shown a clip comprising the oppositely disposed members *4 5* between which the knife-blade terminal *6* of the safety fuse is adapted to be received, the parts *4 5* being provided with parallel sided lugs *7 8* respectively, the ends *9* and *10* of which are out-turned and adapted to be inserted in the undercut recess in the arms of the hereinbefore described attachment, and as shown in Fig. 3, and as will also be apparent, instead of providing the arms *i* and *l* with the undercut recesses, the same may be provided with apertures *2 3* adapted to receive lugs such as the lugs *9* and *10* and which may be suitably secured to or integral with the opposing members of the safety fuse terminal clip, the

operation of the parts and their function being the same as described with reference to the parts Fig. 1.

I claim as my invention:

- 5 1. An attachment for safety fuse clips, comprising two pivotally connected arms, each having a recess therein adapted to receive a part of the safety fuse clip, and means through which pressure may be applied and transmitted to said arms and parts of the said clip to spread the same apart.
- 10 2. An attachment for safety fuse clips comprising two pivotally connected curved arms, each having an undercut recess in its outer edge adjacent to its free end and by which the same is adapted to be connected to the fuse clip, and means through which pressure may be applied and transmitted to

said arms and parts of said clip to spread the latter apart.

- 20 3. An attachment for safety fuse clips comprising two pivotally connected curved arms, each having an undercut recess in its outer edge adjacent to its free end and by which the same is adapted to be connected to the fuse clip and a thumb-piece integral with one of the said arms and by means of which pressure may be applied and transmitted through the arm to the opposing parts of the fuse clip to spread the latter.

Signed by me this 20th day of September, 1907.

WM. J. BOEMPER.
